UNITED STATES PATENT OFFICE.

RUDOLPH F. STEHLIK, OF CHICAGO, ILLINOIS, ASSIGNOR TO RESERVE HOLDING COMPANY, OF KANSAS CITY, MISSOURI, A CORPORATION OF DELAWARE.

AUTOMATIC TELEPHONE SYSTEM.

Application filed May 25, 1927. Serial No. 193,960.

The present invention relates in general to automatic telephone systems, and is concerned more particularly with such systems in which a line finder is employed to connect an idle selecting switch with the terminals of a calling line, and the principal object of the invention, briefly stated, is the provision of a new and improved finder system, which is thoroughly reliable in its operation, and which can be manufactured and maintained at a reasonable cost.

The present invention relates more particularly to finder switches of the full selective type, that is to such a system in which the finder switch is moved first in one direction in search of the level containing the calling line, and then in a coordinate direction in search of the contacts of that line in the selected level.

In one embodiment of my invention I employ as a finder switch, the well known Stronger connector, which is that shown in the Patent 815,176 issued to Keith, Erickson and Erickson, with the circuits and mechanical structure altered in accordance with the objects of my invention.

This type of switch has been used in such systems heretofore, in which systems the finder switches proper were controlled by and through a group of common control equipment. The successful operation of such a system is dependent largely upon the operation of the common control equipment, and if that control equipment becomes defective or out of order, a relatively large group of finder switches, and consequently a larger group of subscriber lines was thrown out of service temporarily. Accordingly, as a further object of my invention I provide a new and improved selective finder system, in which the finder switches are self contained and self controlled, and in which the control equipment common to a group of finder switches is reduced in quantity and function to render the operation of the system more reliable.

In finder switch systems which have been devised heretofore, a large group of finder switches are available to pick-up calls from a group of subscribers' lines, those switches being allotted for service one at a time by means of a finder allotter. The finder allotter so employed constitutes a common control equipment, and if that equipment is faulty a finder switch group is thrown out of service. In recognition of this fact, systems have been devised heretofore with duplicate or tandem finder allotters, which alternately function to allot a finder switch for service. Accordingly a further object of this invention is to provide a new and improved finder allotter of the tandem type, and to provide simplified circuit connections therefor, the improvements tending to render the finder allotter equipment more reliable.

In selective finder systems which have been devised heretofore and of which I am aware, the removal of the receiver from the switch-hook of the calling telephone operates the line equipment, to energize the level relay, to mark the level of the calling line in the finder switch bank. This level marking relay was used in common with all the lines of that particular level. Therefore in a finder switch system having finder switches of a 10-level capacity, ten of such relays are required for each group. The usual plurality of level marking relays runs up the initial cost of the system, and increases the number of contact springs employed, thereby increasing the likelihood of dirty contacts and consequent higher maintenance cost. As a further object of my invention I provide a new and improved level marking arrangement, in which the number of level marking relays has been reduced to one, and the number of contact springs further reduced to render the system less expensive and more reliable.

Further objects of my invention, not specifically mentioned here, will be apparent from the detailed description and claims which follow.

The drawings comprising Figs. 1 and 2, when arranged with Fig. 1 above Fig. 2 with correspondingly numbered lines in alignment, shows sufficient details to enable a clear understanding of my invention.

Referring now particularly to Fig. 1, I show a calling subscriber's line A, terminat-

ing in the bank contacts 28, 29 and 30 of the finder switch, and also in the usual connector banks, which are not shown. Individual to the subscriber's line A are the line and cut-off relays 1 and 2, which are operated responsive to a call upon that line to mark its destination at the finder switch banks and to start the finder switch to connect with it.

10 The finder switch F comprises a Strowger two-motion switch mechanism, actuated by vertical magnet 12, rotary magnet 13 and release magnet 17, and controlled by the four control relays 3, 4, 5, and 6. This finder is 15 equipped with a vertical wiper 53 which engages the contacts of a vertical bank VB as the finder switch shaft (not shown) is stepped upward by the vertical magnet. The 20 mechanical features of this vertical wiper and vertical bank are not new, and do not from an integral part of the present invention. Such a wiper and banks applied to a 25 Strowger connector, is shown on page 69, the 1925 edition of the book "Principles of Automatic Telephony" by Harry B. Mahoney, and a description of its operation is 30 made in the ensuing pages of that text. Finder switch F also carries the customary line wipers 31 and 33 and the private wiper 32, which are rotated into engagement with the contacts of a particular level after that level has been selected by the finder through the agency of the vertical bank. In the 35 circuit shown, the finder switch F is arranged to operate in a vertical direction until the vertical wiper 53 encounters a grounded contact, that contact being grounded by the line equipment of a calling line to mark the level containing that line. When 40 the vertical wiper 53 encounters this grounded contact, the control relays of the finder F are altered so that the vertical magnet is open circuited, and the rotary magnet impelled to drive the wipers 31 to 33 into engagement with the contacts of the selected 45 level. The rotary action of the finder F, continues until the private wiper 32 encounters an ungrounded contact, at which time the 50 finder switches through to establish a connection from the calling line to the selector switch S. The selector switch S, is a well known Strowger selector switch, whose wipers are moved first in a vertical direction under the control of the calling device 55 at the subscriber's station, and then moved automatically in a horizontal direction to select the first idle trunk in the selected level.

Referring now to Fig. 2 I show finder allotters FA¹ and FA², each comprising the 60 double ended wipers which sweep over a row of contacts, and a motor magnet for driving the wipers. Mechanically these finder allotters are like the well known rotary line-switch, whose wipers move in a forward direction only, having no normal position and

being advanced when the driving magnet deenergizes. Associated with the finder FA¹ is the relay 102, which is energized when a call is started, to extend circuits to the pre-selected finder through the finder allotter FA¹. Similarly relay 103 is associated with the finder allotter FA². Relay 101 is associated with the vertical bank circuits, being energized whenever a call is initiated in the group, regardless of the level containing that particular line. The energization of relay 101 projects a grounded circuit through relays 102 and 103 in multiple, one or the other of those relays energizing over that circuit to start the finder switch which it 80 has preselected.

In Fig. 2 I also show the supervisory relay 104, which is energized in series with the release magnet of a finder to extend supervisory circuits as will be pointed out. The 85 banks of finder allotters FA¹ and FA², each have 25 contacts in a row, over which the respective wipers are driven. Thus if it were desired to do so, each finder allotter could establish circuits with 25 separate finder 90 switches. However, since the finder F is of the 100 line type, that is, there are 100 contact sets available to its wipers 21 to 33, it is not necessary that finder allotters FA¹ and FA² each have access to 25 finders. Such an arrangement would give the line group containing line A 50 finder switches, which is more than is necessary. It has been found that traffic in an automatic exchange, can be handled on a 20 percent trunking basis. 100 That is the provision of 20 finder switches for each 100 line group has been found to be adequate. I have therefore set aside these 21st contacts in each bank of the finder allotters as an arresting contact, upon which the 105 finder allotters are stopped, in case all of these finders available to them are busy at the moment. From this arresting contact set, I operate an overflow meter, to record the number of calls lost because all of the 110 finders available to the lines are busy. In the system shown in the present application, I have provided 20 finders, accessible through both of the finder allotters. In the 115 finder allotter FA¹, the finder switches are accessible in a regular order, that is, the wipers 110—112 on rotating in the direction of the arrows, encounters finder switches Nos. 1 to 20 in consecutive order. In finder allotter FA², I have reversed the allotment 120 of the finders, so that the wipers 113 to 114, upon rotating in the direction of the arrows, encounters finder No. 20 first, and then proceeds to the No. 1 contact last, as 125 will be more clearly brought out hereinafter. Since there are 25 contacts in the switch banks, 21 of which have been employed, the remaining four are unused and made permanently busy by ground connection in the 130 banks over which the wiper 110 of the finder

allotter FA¹ sweeps and the wiper 113 of the finder allotter FA² sweeps. A number of finders accessible to the line group containing line A can be increased to 24 by referring to above and connecting the added four finders to the respective bank terminals. If the traffic in the group require more than 24 finders, ordinary principles of trunk grading can be employed, and the added finders provided as required. To do this certain portions of the finders would be common to both finder allotters, and other finders individual to each of the finder allotters, a change of this kind being possible without departing from the scope and spirit of this invention.

Throughout the drawings I have shown a plurality of batteries, to avoid unnecessary complication of the figures. In an installation of the system of my invention, there would be but one battery, preferably with its positive pole grounded.

When the subscriber at station A raises his receiver to initiate a call, line relay 2 is operated over the loop including the calling station, and upon operating removes the ground potential from contact 29, thereby marking that line calling to the finder F, so that switch can establish a connection to it. Since the finder bank number of substation A is assumed to be 85, line relay 2 upon energizing places a ground upon the eight vertical bank contacts over which the vertical wiper 53 sweeps. This ground completes a circuit for the start relay 101 in series with resistance such as 82, to energize that relay to start the finder equipment in motion. It will be noted that normally the contacts of the vertical bank VB are connected to battery potential placed on them through their respective resistances such as 81 and 82, and the start relay 101 in series. When the line A initiated the call the eighth vertical bank contact is changed to ground potential the remaining contacts of the bank being maintained at battery potential by the resistances. By this arrangement the vertical wiper 53 encounters battery potential upon all of the contacts except that associated with the level it is desired to select, that potential serving to short circuit the change-over relay to prevent that relay from energizing and causing the finder to cut-in upon the wrong level.

The energization of start relay 101, throws ground out over conductor 130, thence through the winding of relays 102 and 103 in parallel, the circuit of relay 102 being completed through the winding of motor magnet 105 of the finder allotter FA¹, and the circuit of relay 103 being completed through the motor magnet 106 of the finder allotter FA². One or the other of these relays will be energized, it being assumed that

relay 102 is slightly faster than relay 103, that relay will energize first and upon becoming energized opens the circuit of 103 to prevent its energizing. No special adjustment is provided on relay 102 to make it faster to pull up than relay 103, since it is impossible to build two relays having exactly the same time constants, as would be necessary if both relays 102 and 103 were to become fully energized at the same time. When relay 102 energizes in series with magnet 105, the resistance of the winding of relay 102 prevents the energization of that magnet. Relay 102 closes a circuit for the start relay 4 of the preselector finder F, causing that relay to energize and start the finders stepping in a vertical direction in search of a marked level, that is the level containing the line A. In the finder F, the impulsing relay 5 is energized over circuits completed by the start relay 4, and upon energizing, delivers an impulse of current to the vertical magnet 12, that magnet operating to advance the shaft containing the wipers 31 to 33 and 53 one vertical step. When the vertical magnet 12 has completely energized, it opens interrupter springs 49, thereby interrupting the circuit of relay 5, to permit that relay to fall back and open the circuit of the vertical magnet. Wiper 53 upon being elevated one step encounters battery potential, which is led over the finder circuits to short circuit the change-over relay 6, to prevent that relay from energizing and diverting the impulses from the vertical to the rotary magnet.

When the wiper 53 encounters the level containing the line A, battery potential upon it is changed to ground potential, and relay 6 is energized, in series with relay 5, the energizing circuit of the former serving to hold the latter relay in its energized position. Relay 6 opens the circuit of vertical magnet and changes the impulsing circuit to the rotary magnet, which is immediately energized to advance the wipers one step into the selective level. This arrangement permits the change-over from vertical to rotary motion of the finder with a minimum loss of time, the action is positive, dependent upon the energization rather than upon the deenergization of the change-over relay, as has been the custom heretofore. The rotary magnet energizes, advancing the switch wipers, wiper 32 encountering ground potential as long as it is standing upon the contacts of an uncalling or a busy line. Wiper 32 encounters ground, switching relay 3 is short circuited, to prevent its premature operation. When the contacts of the calling line are encountered, wiper 32 moves its ground potential, and relay 3 energizes to switch the finder through to seize the calling line. The calling subscriber then hears dial tone which is conducted to his telephone over

line conductors 60 and 65, that tone being applied to the lower winding of the line relay 7 of the selector S. The subscriber upon hearing this dial tone operates his calling device in the well known manner, to operate the selector S in accordance with the first digit of the number of the wanted telephone. The operation of selector S is familiar to those skilled in the art, and since it does not form an integral part of this invention will not be enumerated in detail at this time.

Having thus described my invention in general I will now proceed with a detailed description of its operation.

Line A calls.

When the subscriber at substation A removes his receiver to initiate a call, line relay 2 is energized over a circuit traceable from ground through springs 25, line conductor 20, through the calling device, transmitter, receiver and switch-hook of the substation A, negative line conductor 21, springs 23, through the upper winding of relay 2 to battery. Upon energizing, relay 2, at springs 26 and 27 removes ground potential from the private contact 29 in the finder bank, thereby rendering the line A in a calling condition and accessible to the finder switch F. Spring 30 at its make contact closes a circuit from ground through springs 24, conductor 54, resistance 82, conductor 83, through the winding of start relay 101 to battery, energizing that relay preparatory to starting the finder switch in motion. Ground upon the conductor 54, places ground potential on the eighth contact in the vertical bank VB, thereby marking that level to subsequently cause the finder F to stop opposite it and to rotate into it in search of the contact group 28-30. The operation of springs 26, in addition to removing ground potential from the bank of contact 29, extends the release trunk conductor 22 to the normal release conductor 22', thereby preparing circuits over which the line A is subsequently marked busy in the banks of the connector switch.

Starting the finder F.

The energization of start relay 101, closes a circuit from ground through springs 128, conductor 130, through the winding of relay 102, conductor 136, springs 123, conductor 131, through springs 126, through the winding of motor magnet 105 to battery, with a parallel circuit from conductor 130, through relay 103, conductor 134, springs 118, conductor 135, through springs 137, through the winding of magnet 106 to battery. Relays 102 and 103 will both start to energize over the circuit. It is assumed that relay 102 is slightly faster to pull up than relay 103, that relay energizing first, oper-

ates springs 118, thereby opening the above traced circuit through relay 103 to prevent that relay from energizing. Relay 102 upon energizing and operating springs 116, opens a point in the finder preselecting circuit, and prepares a point in the finder allotter kick-off circuit, for a purpose which will be hereinafter explained, and at springs 117 and 118 opens points in the control circuit for finder allotter FA², to prevent that finder allotter from operating at this time. At springs 119, relay 102 prepares a further point in the finder allotter kick off circuit, and at springs 120, closes a circuit from ground through these springs, conductor 137, through wiper 112, now assumed to be in engagement with its 20th bank contact, conductor 71, through the winding of start relay 4, of the finder F, to battery. Relay 4 energizes over this circuit to start the finder.

Vertical impulsing.

The energization of relay 4, closes a circuit for pulsing relay 5, traceable from ground through spring 40 and its make contact, vertical interrupter springs 49, conductor 67, spring 48 and its break contact, springs 41, conductor 68, through rotary interrupter springs 50, through the winding of relay 5 to battery. Relay 5 energizes over this circuit and at springs 42 closes a circuit from ground through spring 45 and its break contact, through the winding of the vertical magnet 12 to battery, energizing that magnet which elevates the shaft (not shown) and wipers 31 to 33 and 53, one vertical step, at the end of which step interrupter springs 49 are opened, and the relay 5 permitted to fall back. The deenergization of relay 5 opens the circuit of the vertical magnet permitting that magnet to fall back and close springs 49, again establish the circuit for the pulsing relay 5. The first operation of the vertical magnet 12 elevates the vertical wiper 53 into engagement with the lower most contact of the bank VB. The energization of relay 4, at springs 41 prepares a point of circuit of switch-over relay 6, that circuit being traceable from battery through relay 5, through rotary interrupter springs 50, conductor 68, through springs 41, springs 48 and its break contact, over conductor 67 to the upper terminal of relay 6. When wiper 53 engages the first contact of the bank VB, battery potential is applied to the lower terminal of switch-over relay 6 over circuits traceable from battery through relay 101, conductor 83, resistance 81, first contact and wiper 53, conductor 63, spring 36 and its break contact, conductor 64, springs 47, to the lower terminal of relay 6. Thus it will be seen that relay 6 is short circuited by having battery potential on both of its terminals, and that therefore it cannot energize and

switch over the pulses from the vertical magnet to the rotary magnet. When the vertical magnet falls back, closes springs 49, it again closes a circuit of relay 5 which was just traced from spring 40 of the relay 4, causing the relay 5 to be reenergized, to close spring 42 to send another pulse to the vertical magnet. During the interval that the vertical magnet is in its normal position and springs 49 are closed, ground from springs 40 is applied to the upper terminal of the lower winding of relay 6, thereby completing a circuit through that winding to battery through resistance 82 and relay 101. However relay 6 was not operate over this circuit because of the relatively high resistance of 82 and relay 101. The operation of relay 5 and the vertical magnet 12 continues, along as wiper 3 encounters battery potential, in this case for seven steps.

Last vertical impulse.

When the vertical magnet and relay have completed seven cycles of operation as above described, they again energize for the eighth time, the magnet 12 advancing the wiper 53 into engagement with the eighth bank contact of the bank VB to which conductor 54 is connected. Since the calling line A terminates in this eighth level, and has placed ground on conductor 54, wiper 53 encounters ground potential instead of battery potential. As soon as the vertical magnet 4 has completely energized and opens springs 49, relay 6 energizes over a circuit traceable from ground, spring 27 and its make contact, springs 24, conductor 54, eighth bank contact and vertical wiper 53, conductor 63, spring 36 and its break contact, conductor 64, springs 47, lower winding of relay 6, conductor 67, spring 48 and its break contact, springs 41, conductor 68, rotary interrupter springs 50, through the winding of relay 5 to battery. Relay 6 is energized over this circuit and relay 5 being in an energized position at the moment the circuit was completed, remains in an energized position. Relay 6 upon energizing locks itself through spring 46 and its upper winding to ground at spring 40 and its make contact, thereby maintaining itself energized independent of the circuit just traced through its lower winding.

Rotary impulsing.

The energization of relay 6 at springs 47 and 48 opens the circuit over which magnet 5 is controlled by the operation of vertical impulse springs 49, spring 48 at its make contact closing a substitute circuit which places the interrupter relay 5 under the control of the finder private wiper 32. Relay 6 and spring 44 places ground upon release trunk conductor 61 for a purpose which will be hereinafter explained. At springs 45, relay 6 opens the circuit of vertical magnet 12, permitting that magnet to fall back. Spring 45 makes contact with its make contact, a circuit is closed for rotary magnet 13, causing that magnet to become energized immediately since relay 5 is held energized, as explained, above and contacts 42 are therefore closed. The energization of rotary magnet 13 advances wipers 31 and 33 one rotary step into the selected level, and operates spring 50 at the end of the step to open the circuit of interrupter relay 5, that relay falling back to terminate the pulse thereby, permitting the rotary magnet 13 to deenergize and at springs 50 reclose the circuit of relay 5. Since the calling line is assumed to have the finder bank designation of 85, contact set 28 to 30, inclusive, is the fifth set in the eighth level, therefore the first four contacts of the level will be grounded, since it is also assumed that the other lines in that level are not calling at the moment. A circuit may now be traced from ground through springs 26 and 27 in multiple, release trunk conductors 22 and contact 29 of the first line in the level, wiper 32, conductor 63, spring 36 and its break contact, conductor 64, spring 48 and its make contact, spring 41, conductor 68, rotary interrupter spring 50, through the winding of relay 5 to battery. Relay 5 energizes over this circuit, at springs 42, closes a circuit through spring 45 and its make contact, through the winding of the rotary magnet 13 to battery, energizing that magnet which advances the wipers 31 to 33 another step and at springs 50 opens the circuit of impulsing relay 5. This action continues for four steps, that is as long as wiper 32 encounters grounded contacts. When switch-over relay 6 is energized, it closes springs 44, places ground upon release trunk conductor 61, that ground potential upon the upper terminal of switch-through relay 3. As long as wiper 32 encounters ground potential, switch-through relay 3 is short circuited, since ground from the wiper 32 through conductor 63, and is placed on the lower terminal over a circuit, springs 36 and its break contact. When the rotary magnet has energized for the fifth time, and advanced the wipers 31 to 33, inclusive, into engagement with contacts 28 to 30, inclusive, of calling line A, wiper 32 loses ground, relay 3 being no longer short circuited energizes over a circuit traceable from grounded release trunk conductor 61, through the winding of relay 3, conductor 64, spring 48 and its make contact, springs 41, rotary interrupter spring 50, through the winding of relay 5 to battery. Relay 3 is of high resistance, and relay 5 is of low resistance, relay 3 therefore energizes over this circuit but relay 5 is prevented from energizing by the high resistance of relay 3. Relay 3 upon energizing closes springs 34 to

39, to switch through the negative and positive line conductors of the finder to trunks 60 and 65, respectively, so that the selector switch S is seized in the usual manner. Relay 3 opens at springs 35 a point in the release circuit of the finder F, and at springs 36 opens the rotary testing circuit and extends the grounded release trunk conductor 61 through those springs to conductor 63, thence over the wipers 32, conductor 22, spring 26, normal release trunk conductor 22' to the connector banks, to mark line A busy in that bank to prevent a connector switch from establishing a connection to it. Relay 3 at springs 37, establishes a shunt around springs 41, 43 and 48, maintains the relay 3 energized independent of the other relays of the finder as long as the release trunk remains grounded.

20 *Finder allotter seeks another finder.*

At springs 38, relay 3 closes a circuit from ground through those springs, conductor 72, through the 20th bank contact and wiper 111 of the finder allotter FA¹, conductor 138, springs 119, conductor 136, springs 123, springs 122, conductor 132, spring 116 and its make contact, through the winding of motor magnet 105 to the finder allotter FA¹ to battery, with a parallel path from spring 123 through conductor 131, interrupter springs 126, through the winding of the magnet 105 to battery. Magnet 105 energizes, prepares to advance the wipers 110 to 112, inclusive, one step. When the finder F switched through to the line A, the circuit of relay 101 was opened, permitting that relay to deenergize and at spring 128 remove the ground from the start conductor 130. The removal of ground from the start conductor 130 permits relay 102 to fall back, and at springs 116 and 119 opens the circuit just traced for allotter motor magnet 112, permitting that magnet to fall back and advance the wipers 110 and 112, inclusive, one step. Since contacts 21 to 24 of the bank over which wiper 110 rotates are grounded, motor magnet 105 is again energized over the circuit traceable from that ground through wiper 110, spring 116 and its break contact, conductor 132, springs 122, conductor 131, interrupter springs 126, through the winding of magnet 105 to battery. Magnet 105 energizes, preparing to advance the wipers another step, and opening springs 126, to permit itself to fall back. Magnet 105 therefore operates in a buzzer like fashion, advancing the wipers step-by-step until wiper 110 fails to pick-up ground potential.

60 *All finders busy.*

Assuming now that the finder F was the last idle finder of the group. When the finder is elevated off-normal by the vertical magnet 12, off-normal springs 52 are oper-

ated, removing ground from the busy common conductor 70, and placing ground upon the conductor 69 to guard the finder and prevent its being picked up by one of the finder allotters. If the finder F was the last idle 70 finder, conductor 70 no longer has ground potential on it, since all the off-normal springs of the group are operated. Therefore when wiper 110 of the finder allotter FA¹ encounters the 25th bank contact, it 75 fails to pick-up ground. Consequently the finder allotter FA¹ comes to rest on contact sets 25, of its bank, remaining there until a finder becomes idle, at which time wiper 110 will again pick up ground from conductor 80 70, and the finder allotter will move on in search of that idle finder.

Since finder F was assumed to be the last idle finder of the group, finder allotter FA² would also be standing on it, since the test 85 wiper 113 of that finder would pick up ground potential on all other contacts of its banks. When the off-normal springs 52 are operated, conductor 69 is placed on ground potential, wiper 113, which is then standing 90 on its sixth bank contact, would pick up that ground, closing a circuit from that ground through that wiper, springs 121, through conductor 133, to the break contact of spring 117 of the relay 112. When the relay 3 of 95 the finder F switches through and opens the circuit of relay 2, as explained above, permitting that relay to fall back, the circuit from conductor 133 is completed through springs 117, conductor 135, interrupter 100 springs 127, magnet 106 to battery. This magnet energizes, interrupting its own circuit at springs 127, and acts in a buzzer like fashion to advance the wipers of finder allotter FA². Since all of the other finders of the group are busy, the wiper 113 will encounter ground on all the contacts between 105 six and twenty-five, inclusive, when it moves into connection with its bank contact 1, to which conductor 70 is connected, it will lose 110 its ground potential and the wipers will come to rest on that contact. Thus it will be seen that both of the finder allotters are aligned upon the resting contact, pending the unbusying of one of the finders of 115 the group. If some subscriber in the group should attempt to call, he will energize the relay 101 as before, throwing the ground upon the start conductor 130, that ground serving to energize relay 102 or relay 103 as 120 before. As soon as relay 102 pulls up, it will at springs 120 place the ground on conductor 137, that ground going through wiper 112 now resting on its twenty-fifth bank contact, over conductor 141 to an overflow 125 meter, registering the call as lost because all the finders of the group were busy at the time it was made. When one of the finders become idle, assume that the finder F is that finder, both finder allotters FA¹ and FA² 130

will position their wipers upon it, finder FA² rotating from contacts 1 to 6 and finder FA¹ from contacts 25 through 1 to 20.

5 *Simultaneous calls.*

Assume now that at the time line A called as described above, another line in the group initiated a call. When a finder F switched through to pick up the line A, relay 101 would not be deenergized as above explained. However relay 102 would fall back since it is short circuited, having ground from conductor 130 upon its lower terminals and ground from wiper 111 through springs 119 upon its upper terminal. As soon as relay 102 falls back, relay 103 energizes over the circuit traceable from grounded conductor 130 through the winding of relay 103, conductor 134, springs 20 118, conductor 135, through interrupter springs 127, through the winding of magnet 106 to battery. The energization of relay 103, opens the circuit over which finder allotter FA¹ seeks another idle finder, this circuit having been traced hereinbefore. Relay 103 closes at springs 125 a finder start circuit for the start relay 4 of the finder which it has preselected, energizing that relay to start its operation of the finder in the manner above described. When the finder has switched through, relay 103 is short-circuited, having ground from conductor 130 upon its lower terminals and ground from wiper 114 through springs 124 to its upper terminal. Relay 103 therefore falls back, and since relay 102 is already back both finder allotters FA¹ and FA² start looking for an idle finder. If another call is pending, relays 102 and 103 will be prevented from energizing by the actuation of the interrupter springs 126 and 127, respectively, by the operation of the magnets of the finder allotters in searching for an idle finder. As soon as one or the other of the allotters finds an idle finder, the relay corresponding thereto will energize, stopping both of the finder allotters in the manner hereinbefore described. Thus it will be seen that in the case of two simultaneous calls, 45 the one is handled by a finder controlled through the finder allotter FA¹ and the other by finder controlled through the allotter FA², and if another call is pending at the time it is controlled through the finder allotter which finds an idle finder first.

55 The above embodiment of my invention has been shown and described by way of example only and I am not to be limited by the specific disclosure shown, as there are 60 many modifications and adaptations apparent to one skilled in the art, which can be made without departing from the scope of my invention.

Having thus described my invention, what

I consider new and desire to have protected 65 by Letters Patent is pointed out in the appended claims:

What is claimed is:

1. In an automatic switch mechanism, two driving magnets each controlling an interrupter spring, an interrupter relay common to said magnets, a circuit for said relay including said interrupter springs in series, wipers on said switch, contacts accessible to said wipers, means for energizing said relay 70 over said circuit to operate the first of said magnets under the control of a certain one of said wipers and interrupter springs, means operated through said certain wiper to shunt said certain interrupter spring and to render 75 said second magnet and interrupter spring operative to position said wipers upon certain ones of said contacts.

2. In an automatic telephone system, a subscriber's line, a finder having access 85 thereto, a primary test contact associated with said line and normally maintained at battery potential, a secondary test contact associated with said line and normally maintained at ground potential, means responsive 90 to the initiation of a call on said line to remove ground from said secondary contact and to apply ground potential to said primary contact to mark said line calling, wipers on said finder having access to said contacts, and means in said finder controlled through said wipers to select said marked contacts and to establish a connection to said line.

3. In an automatic telephone system, a 100 subscriber's line, a finder having access thereto, a primary test contact associated with said line and normally maintained at battery potential, a secondary test contact associated with said line and normally maintained at ground potential, means responsive 105 to the initiation of a call on said line to remove ground from said secondary contact and to apply ground potential to said primary contact to mark said line calling, wipers on said finder having access to said contacts, means in said finder controlled through said wipers to select said marked contacts and to establish a connection to said line, and means responsive to the establishment 110 of said connection to remove said ground potential from said primary test contact.

4. In an automatic telephone system, a subscriber's line, a finder having access 120 thereto, primary and secondary test contacts associated with said line, said contacts normally maintained at opposite battery potentials, means responsive to a call on said line for removing the potential from one of said contacts and applying that potential to the other to mark the line calling, and means in said finder including wipers engaging said

contacts for moving said finder to select said marked contacts and establishing a connection with said line.

5. In a telephone system, a plurality of subscribers' lines arranged in levels, a test contact for each of said levels, a level marking means comprising a relay common to all the levels and connected to the contact of each level through a resistance individual to 10 that contact, a calling line, means associated therewith for marking the contact associated with the level containing that line and for energizing said relay through said resistance, a finder switch started through the 15 energization of said relay, and means in said switch for stopping it when said marked contact is engaged.

6. In a telephone system, a finder switch, a group of subscribers' lines arranged in sub-groups, a testing contact individual to each sub-group, a start relay common to said group and connected to each of said contacts, means responsive to a call on one of said lines to energize said relay and to mark only 20 the contact of the sub-groups containing the line, and means controlled by said relay to start said finder to find said calling line.

7. In a telephone system, a group of lines divided into a plurality of subgroups, a finder switch having a wiper, a group of contacts accessible to said wiper containing a contact for each of said subgroups, a relay common to said contact group and connected to the contacts therein through resistances 35 individual to each contact, means responsive to the initiation of a call on one of said lines to energize said relay through the resistance of the contact associated with the subgroup containing the line and to mark 40 that contact selectable by said wiper, and means controlled by said relay to operate said finder to select said contact and to connect with said calling line.

8. In an automatic switch, a pair of test 45 wipers permanently connected together, contacts accessible to said wipers, relays in said switch controlled through said wipers and contacts over circuits including means for rendering the first of said relays responsive 50 to ground potential and for rendering the second of said relays responsive to zero potential on said wiper, and means operated by said relays to control the operation of said switch.

9. In a telephone system, a finder switch 55 having wipers operable in primary and secondary motions, a primary test wiper and contacts engaged thereby to control the primary motion of said finder, said contacts 60 normally carrying a potential placed thereon by battery through a high resistance, lines accessible to said finder, means responsive to the initiation of a call on one of said lines to mark one of said primary test contacts 65 and to start said finder in its primary mo-

tion, a change-over relay in said finder operated when said primary test wiper engages said marked contact, and means controlled by said relay to stop the primary and start the secondary motion of said finder switch. 70

10. In a telephone system, a finder switch having primary and secondary stepping magnets, interrupter springs controlled by each of said magnets, an interrupter relay, a change-over relay, means for energizing said interrupter relay to start the operation of said finder, over a circuit through said interrupter springs in series and contacts on said change-over relay, means including a primary test wiper and said change-over relay removing said interrupter relay from the control of said primary magnet interrupter springs and for subsequently placing it under the control of said secondary magnet interrupter springs to operate said finder in primary and secondary direction into a desired position. 75 80 85

11. In a telephone system, a group of finder switches, a pair of distributor switches having banks of contacts and wipers which engage said contacts, connections from individual ones of said finder switches to the contacts of the first of said distributor switches in consecutive order and extending to the contacts of the second of said distributor switches in reverse order, means for associating said distributors with idle ones of said finder switches, a line and means responsive to a call thereon to operate one or the other of said distributors to start its associated finder to establish a connection with said line. 90 95 100

12. In an automatic telephone system, a group of finder switches, two distributor switches having access to said finders, banks of contacts on said distributors, the bank contacts of one distributor being connected to the finders in consecutive order and the bank contacts of the other connected in reverse order, means for seizing and operating idle ones of said finder switches through said distributors, means responsive to the operation of the last idle finder of the group to stop said distributors on an over-flow contact, and means operated when one of said finders becomes idle to start said distributors from said over-flow contacts in search of said finder. 105 110 115

13. In an automatic telephone system, a group of subscribers' lines, a group of finder switches having access to said lines, two distributor switches including means for allotting said finders for use one at a time, a start relay associated with each distributor switch, means responsive to the initiation of a call on one of said lines to establish a start circuit to said distributors, said circuit extending through both of said relays in parallel to energize one of them, and means controlled by said energized relay to open the 120 125 130

circuit through the other relay and to start said allotted finder to connect with said calling line.

14. In an automatic switch, a pair of test wipers permanently connected together, a set of contacts accessible to each of said wipers, relays in said switch, circuits for said relays over which the first is caused to respond to and the second prevented from

responding to a given potential on said wipers and the second is caused to respond to zero potential on said wipers, and means controlled by said relays for controlling said switch to establish a connection.

In witness whereof, I hereunto subscribe my name this third day of May, A. D. 1927.

RUDOLPH F. STEHLIK.
